US0D1103842S

(12) **United States Design Patent** (10) **Patent No.:** **US D1,103,842 S**
(45) **Date of Patent:** **** Dec. 2, 2025**

(54) **BUCKLE**

(71) Applicant: **Jianfeng Feng**, Guangdong (CN)

(72) Inventor: **Jianfeng Feng**, Guangdong (CN)

(**) Term: **15 Years**

(21) Appl. No.: **29/917,172**

(22) Filed: **Nov. 17, 2023**

(30) **Foreign Application Priority Data**

Jun. 30, 2023 (CN) 202330406099.5

(51) **LOC (15) Cl.** **02-07**

(52) **U.S. Cl.**

USPC **D11/239**; D11/215; D11/218; D11/219

(58) **Field of Classification Search**

Primary Examiner — Justin M Jonaitis

Assistant Examiner — Grace Doyle

(57) **CLAIM**

The ornamental design for a buckle as shown and described.

DESCRIPTION

FIG. 1 is a front perspective view of a buckle showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof;

FIG. 9 is a perspective view thereof, showing the buckle in a state of use; and,

FIG. 10 is another perspective view thereof, showing the buckle in a state of use.

The broken line showing of straps and hooks in FIGS. 9 and 10 is for the purpose of illustrating environmental structure and form no part of the claimed design.

1 Claim, 10 Drawing Sheets
